United States Patent Office.

ALBAN N. TOWNE, OF CHICAGO, ILLINOIS.

Letters Patent No. 73,940, dated January 28, 1868.

IMPROVED CAR-REPLACER.

The Schedule referred to in these Letters Patent and making part of the same.

TO ALL WHOM THIS MAY CONCERN:

Be it known that I, ALBAN N. TOWNE, of Chicago, in the county of Cook, and State of Illinois, have invented an Improved Apparatus for Putting Cars on the Track; and I do hereby declare that the following is a full and exact description thereof, reference being had to the annexed drawings, making a part of this specification, in which—

Figure 1 is a perspective representation of my improved apparatus for putting cars on the track.

Figure 2 is a transverse section of the same.

Figure 3 is an end view of one of the bars, showing the dog.

The nature of my invention consists in using a long and short bar, to be attached separately to the rails of the road, by means of loops or clasps, in such a manner as to allow the ends of the bars to be placed the required distance from the rails, to accommodate the position of the trucks, which are to be drawn upon the track, and is so arranged as to be conveniently carried upon the cars and readily attached to the rails at any place.

My object is to provide more effectual means for putting cars upon the track than any now in use; and by the use of my invention I claim that cars standing off from the track, within reach of the bars, can be put upon the rails in a very short space of time, thereby making a very great saving of time and labor.

To enable others skilled in the art to make and use my invention, I will describe the method of construction and operation.

A shows the bed of the road, on which the ties B are laid. C represents the common T-rails now used in the construction of railroads. E shows the clasps, which are formed to fit the upper part of the rails C, allowing spaces for the keys J, which are made similar to those used in fastening the rails in the old style of chair. D represents the bars, attached to the clasps E, by means of the bolts I, so as to allow the bars to be placed in any desired position upon the track or bed of the road A. The opposite ends of the bars D, from the clasps E, are made more thin than the other parts, and terminate in the dogs H, which are driven into the ties or road-bed, when the apparatus is in use, so as to prevent a lateral motion of the bars. I make the bars D from iron or steel, two by two and a half inches in size, and any length desired, but generally make the short bar three-fourths of the length of the long one. The object of making one of the bars longer than the other, is to allow only one truck-wheel to pass over the ends of the bars upon the rails C, at a time, thus preventing the possibility of the trucks sliding from the rails, which might be the case if the bars were of equal length. The clasps E should be made of wrought iron, or of similar material, and in such a manner that they can be loosened from the rails C, by removing the keys J.

Operation.

In order to use my invention, it is first necessary to secure the clasps E to the rails C, as shown in the drawings, then swing the ends of the bars directly in front of the truck-wheels, and drive the dogs H into the tie or road-bed, which will prevent a longitudinal or lateral motion of the bars. The cars can then be drawn on the track C, by means of the engine, in the usual manner. The key J must be removed, after which the bars can be detached from the track. G F represent the truck-wheels in the position they are supposed to occupy when being elevated upon the track. X shows the direction the wheels are to move.

Having thus described my device, what I claim, and desire to secure by Letters Patent, is—

An apparatus for replacing cars upon the track, formed by a combination of the clamp E and bars D, the former to be attached adjustably to the rail by keys J, and the latter made of unequal lengths, and terminating with dog H, for attaching them to the track, substantially as set forth.

ALBAN N. TOWNE.
